CAR COUPLER

Arthur J. Bazeley, Shaker Heights, Ohio, assignor to National Malleable and Steel Castings Company, Cleveland, Ohio, a corporation of Ohio

Application March 7, 1936, Serial No. 67,586

16 Claims. (Cl. 213—167)

This invention relates to coupler mechanisms and is more particularly concerned with provisions of an improved arrangement for rotary operation of the locks of A. A. R. standard type "E" couplers. In the Bazeley Patent No. 2,000,435, dated May 7, 1935, there is disclosed a rotary operating means for the lock, which means comprise a rotor lift lever mounted on a trunnion integral with a pair of flanges depending from the under side of the coupler.

In the patent an uncoupling rod is releasably secured to either side of the rotor lift lever whereby the same may be operated from either side of the car. In the standard type "E" coupler most freight cars use only one uncoupling rod and the operation is therefore from only one side of the car. Some difficulty has at times been experienced in such cases by the rotor lift lever jamming between the integral trunnion and a transverse wall joining the depending flanges at a point above the trunnion. This jamming usually occurs after the couplers have been in service for some period and have had an opportunity for the parts to rust. It is, in part, caused by the weight of the uncoupling rod, where only one is used, which is applied to the lever laterally beyond its point of support on the trunnion, such weight tipping the rotor lift lever laterally until the upper part of the hook-shaped portion thereof which is intended to engage the trunnion, contacts with the aforesaid wall above the trunnion on the guard arm side of the coupler. On the opposite end of the trunnion, that is, the side nearest the knuckle, the rotor lift lever remains in contact with the trunnion. When an attempt is made to operate the rotor lift lever by means of the uncoupling rod, the lever instead of sliding smoothly around the trunnion, jams between the aforesaid two points and is at times impossible to operate so as to unlock the coupler. This condition is further aggravated for the reason that the contact between the rotor lift lever and the hook-shaped portion of the uncoupling rod is such that upon initial movement of the rotor lift lever a couple is produced tending further to tip the rotor lift lever so as to cause jamming between the wall and trunnion.

I have provided an improved construction applicable to "E" couplers now in service and which effectively overcomes this difficulty and permits the lock to be at all times moved to unlocking and knuckle throwing positions without jamming of the parts. In my improved arrangement the uncoupling rod is supported on the 55 rotor lift lever as close as possible to the guard

arm side thereof. Moreover, there is provided means whereby the contact between the uncoupling rod and lever causes a couple to be exerted, upon operation of the uncoupling lever, that holds the hook-shaped portion of the lever in engagement with the trunnion throughout the unlocking and knuckle throwing movements. The invention also contemplates means for preventing tipping of the uncoupling lever, particularly when it is in its normal locked position and at the end of knuckle throw. Other features of the invention will be hereinafter described and claimed.

In the accompanying drawings:

Figure 1 is a vertical sectional view of a standard A. A. R. type "E" coupler embodying my invention, the coupler lock being shown in locking position.

Figure 2 is a bottom plan view of the coupler of Fig. 1.

Figure 3 is a fragmentary sectional view of the coupler shown in Fig. 1, showing the uncoupling lever in partially rotated position.

Figure 4 is an end view of my improved lifter having a portion thereof broken away, showing the engagement with the integral trunnion.

Figure 5 is a perspective view of my improved lifter member.

Figure 6 is a plan view of this same lifter, and

Figure 7 is a front elevation showing a coupler, with my improved lifter, applied to a car.

Referring to the drawings, there is shown a standard A. A. R. type "E" coupler having a head 1 to which a knuckle 2 is pivoted by means of a pin 3. Cooperating with the knuckle in the usual way is a lock 4 having a depending leg 5 extending downwardly into a slot provided in the bottom of the coupler. The lock 4 in locking position rests with its rear shoulder 6 upon the knuckle thrower 7. The cooperation of these parts all being standard are well known and will not be further described.

Extending downwardly from the under side of the coupler are a pair of transversely spaced flanges 8, 8 having an integral trunnion 9 extending therebetween. Above the trunnion is a transversely extending wall 10 having an under surface 11 substantially concentric with the trunnion 9. The rotor lift lever 12 has a hook-shaped portion 13 at one end, adapted to be pivotally mounted on the trunnion 9. Extending forwardly and upwardly at the opposite end of member 12 is an arm 14 provided at its upper end with an opening 15 for reception of the trunnion 16 on a toggle member 17. The opposite end of the

toggle member is operatively connected to the leg of the lock in the usual manner by means of a trunnion 8 that extends laterally into slot 19 in the leg 5 of the lock. Joining the hook portion 13 and the arm 14 are flanges 20, and 21, which flanges are positioned substantially at right angles to each other, the flange 20 being in a substantially vertical plane. The hook portion 13 may be reinforced by upwardly extending flanges 22, and 23, that merge into the flanges 20, and 21. Between the flanges 20, and 21, is an opening 24 for reception of the uncoupling rod 25. Extending laterally from the arm 14 is a shelf 26, which is in effect a downwardly extending continuation of flange 21.

The uncoupling rod 25 is bent in a reverse direction to form a U-shaped portion 27. This U-shaped portion is passed through the opening 24 in the member 12, the rod 25 normally resting on the top of flange 21, as shown in Fig. 1 at 30.

In operating the device, the rod 25 is rotated from the side of the car in the usual manner and contacts the lever 12 in two places, producing a couple which causes the lever to be moved about its pivot to actuate the lock. In previous constructions the two points of contact between the U-shaped portion of the rod and the rotor lift lever were diagonally opposite so that a vertical plane drawn through the points of contact A, B would extend diagonally forwardly toward the guard arm side of the coupler, as illustrated by the line X—X in Fig. 6. In my improved construction the rod 25 contacts the rear of the opening 24, that is, the portion nearest the hook 13, at a point substantially midway between the longitudinal center line of the hole and the knuckle side thereof. This is substantially the same point of contact as in previous constructions, but since the flange 20 is positioned as far laterally toward the guard arm side of the coupler as is possible within the limitations present in the couplers now in service, I am enabled to move the opening 24 the maximum distance toward the guard arm side of the member 12 so that in effect the contact between the rod and lever at the rear of the hole 24 is moved toward the guard arm side of the coupler. Instead of the portion 27 of the rod contacting the forward wall of the opening 24, as in previous constructions, I provide this contact between the under surface 28 of shelf 26 and the end 29 of the portion 27 of the rod. I prefer to have this contact take place between the end 29 and the outer extremities of surface 28. This may be provided either by tapering the surface 28, as shown in Fig. 2, or by bending the end 29 of the rod slightly forwardly. It will be seen that the two points of contact C, D between rod 25 and member 12, with my improved construction, lie in a vertical plane extending diagonally forwardly toward the knuckle side of the coupler, as illustrated by line Y—Y. As a result, a couple is produced on the member 12, which not only rotates it about the trunnion 8 but also tends to tip the member 12 in a clockwise direction, as viewed in Fig. 4. This latter couple maintains the contact between the under surface 31 of the hook portion 13 and the trunnion 8 over the entire lateral extent of surface 31, particularly on the guard arm side of the coupler where difficulty has been experienced with other constructions. It has been found from actual trials that there is no tendency for the rotor lift lever 12 to be lifted free of the trunnion on either side thereof.

It will thus be seen I have provided means whereby the contact between the rotor lift lever and the trunnion is maintained throughout the lock lifting and knuckle throwing movements, whereby the difficulty experienced from the wedging of the lever between the trunnion 8 and wall 10 is eliminated. To further insure maintenance of this contact, and particularly during the time when the rod is not being operated and also during the preliminary movement thereof, I provide projections or heels 32—32 at the inner end of the hook 13, underlying a portion of the trunnion 8. It will be clearly appreciated that the effect of these projections is to prevent vertical movement of the lever 12 when the latter is in its normal unoperated position. In fact, they prevent movement of the lever away from the trunnion in the plane of the U-shaped portion 27 after the latter has contacted the surface 28, as shown in Fig. 3. As the lever 12 moves around the trunnion, the aforementioned plane will, of course, move with it so that in any position of the lever from normal to unlocked position the projections 32 will assist in maintaining the contact between the lever and trunnion.

In Fig. 7, I have shown a coupler provided with my improved lifter applied to a car. The uncoupling rod 25 is shown supported at its inner end solely by the rotor lift lever 12 and at its outer end by a bracket 33 secured to the car at a point higher than the rotor lift lever. The axis of rotation of the rod is therefore inclined to the axis of rotation of lever 12. It will be clear from the preceding description that forces will be exerted by the rod on the lever which will tend to cause the latter to rotate about an axis parallel to the axis of rotation of the rod. The bracket is constructed so as to permit lateral sliding movement of the rod with lateral movements of the coupler.

I have therefore provided a rotor lift lever of improved construction which may be used on any of the standard type "E" couplers now in service, without any modification thereof and which effectively overcomes the binding or jamming of the lifter between the trunnion about which it is pivoted and the wall above the trunnion. Such construction permits smooth operation of the rotor lift lever at all times, even when the parts have become rusted under service conditions.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car coupler, a pivoted knuckle, a lock for said knuckle, a pair of downwardly extending walls on the bottom of said coupler and an integral trunnion connecting said walls, a lever pivotally mounted on said trunnion and operatively connected to said lock, and an uncoupling rod supported at one end by said lever for operating the same, said rod and lever being so constructed and arranged that upon operation thereof the points of contact between said rod and lever lie in a vertical plane extending diagonally forwardly toward the knuckle side of the coupler.
2. A rotor lift lever for car coupler having a hook-shaped portion at one end for pivotal mounting on the coupler and an arm at its oppo-

site end adapted to be operatively connected to the lock of the coupler, a pair of walls connecting said portion and arm and forming an opening therebetween, and a flange extending down-
5 wardly and forwardly away from said opening, and laterally away from said opening toward the knuckle side of the coupler when said lever is assembled in a coupler.

3. A rotor lift lever for car coupler having a hook-shaped portion at one end for pivotal mounting on the coupler and an arm at its opposite end adapted to be operatively connected to the coupler lock, a pair of walls connecting said portion and arm and forming an opening 10 therebetween, one of said walls, when said lever is in operative position, lying substantially in a vertical plane and a flange extending downwardly and forwardly away from said opening, and laterally away from said opening toward the knuckle 15 side of the coupler when said lever is assembled in a coupler.

4. A rotor lift lever for car coupler having a hook-shaped portion at one end for pivotal mounting on the coupler and an arm at its opposite end adapted to be operatively connected to the lock of the coupler, a pair of walls connecting said portion and arm and forming an opening therebetween, said walls being substantially at right angles to each other, and a flange 20 adjacent said arm extending downwardly at an angle to one of said walls.

5. In a car coupler including a knuckle and a lock, a rotor lift lever for said lock having a hook-shaped portion at one end thereof, means on said 25 coupler adapted to receive said portion for pivotally mounting said lever on said coupler to the rear of said lock, and means comprising a projection on said lever underlying a portion of said pivotal means for limiting movement of said lever 30 away from said pivotal means.

6. In a car coupler including a knuckle and a lock, a trunnion on said coupler, a rotor lift lever for said lock pivotally mounted on said trunnion and having an opening for receiving an uncoupling rod, an uncoupling rod passing through said 45 opening and having a portion resting on said lever on the knuckle side thereof and tending to rotate said lever laterally of the coupler and means comprising a projection on said lever underlying said trunnion for limiting said lateral 50 rotation.

7. In a car coupler including a knuckle and a lock, a rotor lift lever operatively connected to said lock, means for pivotally mounting said lever 55 on said coupler, and uncoupling rod for operating said lever, said lever having an opening receiving said rod, a flange on the knuckle side of said lever adapted to be engaged by a portion of said rod, the metal forming said opening, the rod, and 60 said flange being constructed and arranged so as to maintain said lever in surface contact with said pivotal means during operative movements of said lever to counteract the tendency of said rod to tip said lever.

65 8. In a car coupler including a knuckle and a lock, means for operating the lock comprising a rotor lift member and a toggle connecting said member and lock, said coupler having a trunnion and said member having a hook-shaped portion 70 for engaging said trunnion to pivotally support said member thereon, an uncoupling rod supported on said member, said rod and member being constructed and arranged so that on actuation of said uncoupling rod the latter will engage said member at such points as to exert forces 75

thereon tending to maintain the hook-shaped portion of said member in engagement with said trunnion throughout the lateral extent of said portion.

9. In a car coupler including a knuckle and a lock, means for operating the lock comprising a rotor lift member and a toggle connecting said member and lock, said coupler having a trunnion and said member having a hook-shaped portion 5 for engaging said trunnion to pivotally support 10 said member thereon, an uncoupling rod supported on said member, said rod and member being constructed and arranged so that on actuation of said uncoupling rod the latter will engage said member at points lying in a vertical 15 plane extending diagonally forward toward the knuckle side of the coupler to thereby exert forces on said member in such a direction as to maintain the hook-shaped portion of said member in engagement with said trunnion through 20 the lateral extent of said portion.

10. In a car coupler including a knuckle, lock and a guard arm opposite said knuckle, a rotor lift member pivotally supported on said coupler 25 for operating the lock, and an uncoupling rod supported on said member, said rod and member being constructed and arranged so that on actuation of said uncoupling rod the latter will engage said member at points spaced longitudinally and laterally thereof, the point of engagement nearest the hook-shaped portion being 30 farther towards the guard arm side of said member than the other point of engagement.

11. A rotor lift lever for car coupler having a hook-shaped portion at one end for pivotal mounting on a coupler and having an arm at its opposite end adapted to be operatively connected to a coupler lock, a pair of walls joining said portion and arm and forming an opening therebetween, the laterally outer surface of each wall 40 lying in substantially the same plane as the laterally outer surface of said hook-shaped portion on the same side of said lever, said opening being closely adjacent the wall of said lever on the guard arm side of the coupler when said lever is 45 assembled in a coupler.

12. A rotor lift lever for car coupler having a hook-shaped portion at one end for pivotal mounting on the coupler and an arm at its opposite end adapted to be operatively connected 50 to the lock of the coupler, a pair of walls connecting said portion and arm and forming an opening therebetween, one of said walls being substantially vertical and having its laterally outer surface substantially in the plane of the laterally outer surface of said hook-shaped portion on the same side of said lever, and the other of said walls being substantially horizontal and having its laterally outer surface in substantially 55 the plane of the laterally outer surface of said hook-shaped portion on the same side of said lever, said opening being closely adjacent the wall of said lever on the guard arm side of the coupler when said lever is assembled in a coupler.

13. A rotor lift lever for car coupler having a hook-shaped portion at one end for pivotal mounting on the coupler and an arm at its opposite end adapted to be operatively connected to the lock of the coupler, a pair of walls connecting said portion and arm and forming an opening therebetween, one of said walls being substantially vertical and having its laterally outer surface substantially in the plane of the laterally outer surface of said hook-shaped portion on the same side of said lever, and the other of said 75

walls being substantially horizontal and having its laterally outer surface in substantially the plane of the laterally outer surface of said hook-shaped portion on the same side of said lever, said vertical wall being on the guard arm side of the coupler and said opening being closely adjacent said vertical wall.

14. A rotor lift lever comprising a plurality of arms one of which is adapted for pivotal connection with the under side of a car coupler, and the other of which is adapted for connection with the leg of a lock, said arms converging downwardly and being joined by a plurality of walls with an opening between said walls, and a flange extending away from said opening and laterally of the second-named arm toward the knuckle side of the coupler when said lever is assembled in a coupler.

15. In coupler operating mechanism, a lock operating lever mounted on the under side of a car coupler for rotation about a horizontal axis, an uncoupling rod mounted at one end in a bracket adjacent the side of the car and above said horizontal axis and at its other end being carried by

said lever, the axis of rotation of said rod being inclined to the axis of rotation of said lever, and the connection between said rod and lever being so constructed and arranged that upon rotation of said rod the latter will engage the lever at such points as to exert forces thereon tending to cause said lever to rotate about an axis substantially parallel to the axis of rotation of said rod.

16. In coupler operating mechanism, a lock operating lever mounted on the under side of a car coupler for rotation about a horizontal axis, an uncoupling rod mounted at one end in a bracket adjacent the side of the car and at its other end being carried by said lever, the axis of rotation of said rod being inclined downwardly toward the coupler, and the connection between said rod and lever being so constructed and arranged that upon rotation of said rod the latter will engage the lever at such points as to exert forces thereon tending to cause said lever to rotate about an axis inclined downwardly toward the guard arm side of the coupler.

ARTHUR J. BAZELEY.
